COLLAPSIBLE GARMENT HANGER

William Gersohn, Yonkers, N. Y.

Application March 12, 1945, Serial No. 582,223

9 Claims. (Cl. 223—89)

1

This invention relates to new and useful improvements in garment hangers and has more particular reference to a collapsible garment hanger.

The new and improved collapsible garment hanger is particularly intended for manufacturers, wholesalers, and retailers of ladies' and children's dresses. At the present time this class of trade is using inexpensive cardboard hangers. It is customary to support large groups of dresses by these hangers next to each other on support racks. When it becomes necessary to ship the garments, the hangers should be removed. However, the hangers cannot be easily removed, because usually the neck openings of the dresses are too small to permit convenient removal through the neck. It then becomes necessary to remove the hangers through the bottoms of the garments. The labor cost in so removing the hangers, and in individually handling the garments to do this, is higher than the cost of the paper hangers. For this reason it is customary in the trade to break one of the shoulder pieces of the cardboard hangers so that they may be easily removed through the neck openings of the garments.

While the hangers are relatively cheap, they add up to quite an item with manufacturers, reaching upwards of \$500.00 a month for even medium sized firms. For this reason some concerns attempt to salvage the broken hangers by placing two broken hangers together and securing them together with staples. Now these mended double hangers are used in the same way as the original hangers. When it becomes necessary to ship the dresses they are broken and discarded. Some firms do not even bother to break hangers, but ship the garments with the hangers in them.

This invention proposes collapsible garment hangers which may be easily collapsed while maintaining positions upon a supporting rack permitting the hangers to remain in position, on the supporting rack while the dresses are slipped down off the collapsed hangers. It is proposed to so construct the collapsible hangers that a group of dresses may be grasped at one time, for example, a half a dozen, or so, and simultaneously the hangers of the entire group may be collapsed so that each individual hanger may remain on the rack, as the dresses are removed. This is a great saving in labor, and in hangers. It eliminates the necessity of breaking the hangers for quick removal through the neck openings. The fact that they may be collapsed while a group of dresses is being handled,

2

is another important feature, since this operation is much faster than one requiring that each garment hanger be individually collapsed.

More particularly, it is proposed to characterize the new collapsible garment hanger by the fact that it includes a stationary section, preferably consisting of a shoulder piece connected with the supporting hook of the hanger, and a pivotally connected section, consisting of the other shoulder piece, which is pivotally connected with the stationary section to swing upwards and downwards. A very important feature of the invention resides in the fact that interengageable limiting elements are provided on the stationary section and on the pivotal shoulder piece arranged normally to support the pivotal shoulder piece in a horizontal position, and said limiting elements being resiliently urged to separate from each other when the pivotal shoulder piece is lifted a short distance, whereupon the pivotal shoulder piece is freed, and may be collapsed downwards. Now the hanger may be removed through the neck opening. It will be readily seen that with this new construction a group of dresses may be held by the stationary sections of the hangers, and the pivotal sections may be pivoted upwards, through the material of the garments, by one motion of the hand, so that all of the pivotal shoulder pieces are freed and may be pivoted downwards permitting the entire group of hangers to be removed through the neck openings of the garments.

The invention contemplates numerous modified forms. In one such form, the new and improved collapsible garment hanger is constructed of cardboard, fiberboard, thermo-plastic or other similar sheet materials. In another form it is constructed of wire resembling very much a common wire garment hanger. In still another form, the new cardboard garment hanger is reinforced with metal clips at the points, or areas where the pivotal shoulder piece engages against, or rests upon the stationary section of the garment hanger.

Still further the invention proposes the construction of a new and improved garment hanger as briefly described, which is exceptionally simple, relatively durable, very desirable and which may be manufactured and sold at a low cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a collapsible garment hanger, constructed in accordance with this invention.

Fig. 2 is a fragmentary enlarged end view of Fig. 1, looking in the direction of the line 2—2 thereof.

Fig. 3 is a side elevational view similar to Fig. 1 but illustrated with the pivotal shoulder piece 10 in a raised position.

Fig. 4 is an end view looking in the direction of the line 4—4 of Fig. 3.

Fig. 5 is an elevation view of another collapsible garment hanger constructed in accordance with 15 a modified form of this invention.

Fig. 6 is a fragmentary sectional view taken on the line 6—6 of Fig. 5.

Fig. 7 is another side elevational view of still 20 another collapsible garment hanger embodying another form of this invention.

Fig. 8 is a side elevational view of the pivotal shoulder piece of the hanger shown in Fig. 7.

Fig. 9 is a side elevational view of the stationary section of the hanger shown in Fig. 7.

The collapsible garment hanger, in accordance with that form of the invention illustrated in Figs. 1 to 4 inclusive includes a stationary section 10 consisting of a shoulder piece 11 connected with and supported by a hook 12. A movable shoulder piece 14 is pivotally connected by a pintle member or rivet 15 with the stationary section 10 to swing upwards and downwards. Interengaging limiting elements 16 and 17 on the pivotal shoulder piece 14 and on the stationary section 10, respectively, normally support the pivotal shoulder piece 14 in a horizontal position. These interengaging limiting elements 16 and 17 are resiliently urged to separate when the shoulder piece 14 is moved, or lifted. When thus moved the shoulder piece 14 is freed, and the hanger may be collapsed.

The limiting elements 16 and 17 are in the nature of projecting portions, which are adapted to hook together, or engage each other in any way, so as to limit pivoting or moving of the shoulder piece 14. The inherent resiliency of the material from which the stationary section 10, or the movable shoulder piece 14, or both of these parts are made, is depended upon to provide the necessary resiliency for urging the limiting elements 16 and 17 apart. For this reason it is necessary that the shoulder piece 14 and the stationary section 10 to be slightly manually twisted, relative to each other, when the shoulder piece 14 is moved downwards, to set the hanger into its operative position. For example, in Fig. 3 it is necessary that the shoulder piece 14 be pivoted backwards relative to the stationary section 10 to interengage the limiting elements 16 and 17. These elements are shown interengaged in Figs. 1 and 2. Whenever the shoulder piece 14 is raised to the position shown in Fig. 3, or above this position, the parts return to their normal positions, as illustrated in Fig. 4, in which the stationary section 10 is in a plane adjacent the movable shoulder piece 14. Now the shoulder piece 14 may be pivoted downwards for collapsing the hanger. The stationary section 10 and the movable shoulder piece 14 may be constructed of cardboard, fiberboard, thermoplastic or other boards, or materials, which are somewhat springy.

In Figs. 5 and 6 a modified form of the invention has been disclosed which is very similar to 75

the prior form distinguishing merely in the fact that reinforcement clips 19, preferably made of sheet metal, are engaged upon the contacting edge portions of the interengaged limiting elements 16 and 17. These clips reinforce the edge portions preventing rapid wearing out, or bending or damaging of the contacting edge portions. In this way the life of the hanger is increased. Furthermore, because of the reinforcement clips 19 it is possible to construct the hangers of thinner, or lighter weight cardboard, or other desirable materials.

In Figs. 7 to 9 inclusive, still another form of the invention has been disclosed which is very similar to the prior form distinguishing merely in the fact that the garment hanger is constructed of wire instead of sheet material. This new wire garment hanger has a stationary section 20 consisting of a shoulder piece 21 connected with a hook 22. A movable shoulder piece 24 is pivotally connected with the stationary section 20 by a pintle member, or rivet 25 so that it may swing upwards and downwards. The stationary wire section 20 follows the outline of the corresponding stationary sections in the prior forms of the invention, departing merely in the fact that the wire continues into a loop portion 30 used as a socket for the pintle member, or rivet 25. The shoulder piece 24 also follows the contour of the movable shoulder pieces in the prior forms of the invention departing in the provision of a loop 31 to form another socket for the pintle member, or rivet 25. The shoulder pieces 21 and 24 overlap sufficiently so that they support each other while pivoting and assist the pintle member or rivet 25 in firmly pivotally connecting the shoulder pieces. The shoulder piece 24 and the stationary section 20 have interengaged limiting elements 26 and 27, respectively, which normally engage each other for supporting the shoulder piece 24 in its horizontal position. These interengaged limiting elements 26 and 27 are resiliently urged to separate due to the inherent resiliency of the stationary section 20 and the movable shoulder piece 24, when the shoulder piece 24 is lifted, or moved, whereupon the shoulder piece 24 is freed and may be moved downwards.

The operation of the new and improved collapsible garment hanger may be understood from the following:

It is intended that the new hangers be particularly used where large quantities of ladies' and children's dresses are manufactured or handled. Such users would be manufacturers, wholesalers, and retailers. The new garment hanger may be individually inserted into the neck opening of the garment by moving the movable shoulder piece into a collapsed position. Then the movable shoulder piece may be raised and slightly twisted relative to the stationary section of the hanger to cause the interengageable elements to interengage each other and lock, or hold the movable shoulder piece in its horizontal position. The garments may now be hung up by the hangers upon support racks, or other places.

When it becomes necessary to ship, or handle large quantities of dresses, the hangers may be removed. To do this, a group of the hangers are gripped with one hand and with the other hand the movable shoulder pieces are raised through the material of the garments. This causes the interengaged limiting elements to disengage from each other automatically because they were resiliently being urged into separated positions while the movable shoulder pieces were in their horizon-

tal positions. Now that the movable shoulder pieces are free, they may be collapsed downwards and the hangers quickly drawn out of the dresses, or other garments.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a garment hanger having a stationary section, a shoulder piece movably connected with said stationary section to swing upwards and downward, and interengaged limiting elements on said stationary section and on said shoulder piece supporting said shoulder piece in a horizontal position, and said limiting element on said shoulder piece being directed downwards and resiliently urged laterally to separate said other limiting element when said shoulder piece is lifted, whereupon said shoulder piece is freed to be collapsed downwards.

2. In a garment hanger having a stationary section, a shoulder piece movably connected with said stationary section to swing upwards and downwards, and interengaged limiting elements on said stationary section and on said shoulder piece supporting said shoulder piece in a horizontal position, and said limiting element on said shoulder piece being directed downwards and resiliently urged laterally to separate said other limiting element when said shoulder piece is lifted, whereupon said shoulder piece is freed to be collapsed downwards, said interengaged limiting elements being integral with said stationary section and with said movable shoulder pieces.

3. In a garment hanger having a stationary section, a shoulder piece movably connected with said stationary section to swing upwards and downwards, and interengaged limiting elements on said stationary section and on said shoulder piece supporting said shoulder piece in a horizontal position, and said limiting element on said shoulder piece being directed downwards and resiliently urged laterally to separate said other limiting element when said shoulder piece is lifted, whereupon said shoulder piece is freed to be collapsed downwards, said movable shoulder piece being inherently springy to provide said resilient urge.

4. In a garment hanger having a stationary section, a shoulder piece movably connected with said stationary section to swing upwards and downwards, and interengaged limiting elements on said stationary section and on said shoulder piece supporting said shoulder piece in a horizontal position, and said limiting element on said shoulder piece being directed downwards and resiliently urged laterally to separate said other limiting element when said shoulder piece is lifted, whereupon said shoulder piece is freed to be collapsed downwards, said stationary section being inherently springy to provide said resilient urge.

5. In a garment hanger having a stationary section, a shoulder piece movably connected with said stationary section to swing upwards and downwards, and interengaged limiting elements

on said stationary section and on said shoulder piece supporting said shoulder piece in a horizontal position, and said limiting element on said shoulder piece being directed downwards and resiliently urged laterally to separate said other limiting element when said shoulder piece is lifted, whereupon said shoulder piece is freed to be collapsed downwards, said stationary section and said movable shoulder piece being inherently springy to provide said resilient urge.

6. In a garment hanger having a stationary section, a shoulder piece movably connected with said stationary section to swing upwards and downwards, and interengaged limiting elements on said stationary section and on said shoulder piece supporting said shoulder piece in a horizontal position, and said limiting element on said shoulder piece being directed downwards and resiliently urged laterally to separate said other limiting element when said shoulder piece is lifted, whereupon said shoulder piece is freed to be collapsed downwards, said stationary section and said movable shoulder piece being inherently springy to provide said resilient urge.

7. In a garment hanger having a stationary section, a shoulder piece movably connected with said stationary section to swing upwards and downwards, and interengaged limiting elements on said stationary section and on said shoulder piece supporting said shoulder piece in a horizontal position, and said limiting element on said shoulder piece being directed downwards and resiliently urged laterally to separate said other limiting element when said shoulder piece is lifted, whereupon said shoulder piece is freed to be collapsed downwards, said stationary section and said movable shoulder piece being inherently springy to provide said resilient urge.

8. In a garment hanger having a stationary section, a shoulder piece movably connected with said stationary section to swing upwards and downwards, and interengaged limiting elements on said stationary section and on said shoulder piece supporting said shoulder piece in a horizontal position, and said limiting element on said shoulder piece being directed downwards and resiliently urged laterally to separate said other limiting element when said shoulder piece is lifted, whereupon said shoulder piece is freed to be collapsed downwards, said stationary section and said shoulder piece being of wire material, and loop portions being formed in said wire material to form socket openings, and a pintle member engaged through said socket openings for pivotally connecting said movable shoulder piece with said stationary section, and said shoulder piece and stationary section overlapping for assisting said pintle member in firmly pivotally connecting said parts.

9. In a garment hanger having a stationary section, a shoulder piece pivotally connected with said stationary section to swing upwards and downwards, and interengaged limiting elements on said stationary section and on said shoulder piece supporting said shoulder piece in a horizontal position and resiliently urged to separate when said shoulder piece is moved upwards, whereupon said shoulder piece is free to be collapsed downwards.

WILLIAM GERSOHN.
